Inventor
John M. Sullivan
Pondeliville, Mass.

UNITED STATES PATENT OFFICE.

JOHN M. SULLIVAN, OF CULVER, INDIANA.

WATER-TUBE BOILER.

Application filed August 26, 1920. Serial No. 406,113.

To all whom it may concern:

Be it known that I, JOHN M. SULLIVAN, a citizen of the United States, residing at Culver, in the county of Marshall and State of Indiana, have invented certain new and useful Improvements in Water-Tube Boilers, of which the following is a specification.

This invention relates in general to steam boilers, and more particularly to the water tube type, the invention being concerned principally with the baffles which are employed to direct the passage of the products of combustion around the tubes for the purpose of promoting the efficiency of the boiler.

One of the primary objects of my present invention is to provide baffles for the purpose indicated, which will be fluid cooled so as to prevent them from burning out, thereby insuring a long period of use, and which shall be so constructed that the removal and replacement of the boiler tubes when necessary will not be interfered with by the baffles.

Another object of the invention is to provide baffles which shall be so constructed and connected up that a continuous flow of fluid through the baffles will be maintained, the flow being counter to the direction of the passage of the products of combustion around the baffles to insure the maximum heat exchange, thereby securing a high efficiency of the boiler.

A further object is to so connect up the baffles that the fluid circulating therethrough and heated therein may be utilized in promoting the efficiency of the apparatus.

Other objects and many of the attendant advantages of this invention should be readily appreciated as the same becomes better understood by reference to the following description when considered in connection with the accompanying drawings.

Referring to the drawings,

Fig. 1 is a longitudinal view partially in section of a boiler equipped with my invention; and

Fig. 2 is a similar view showing a different embodiment of my invention.

By reference to the drawings more in detail and particularly to Fig. 1, thereof, it will be observed that the boiler disclosed is of the usual water tube type, comprising the tubes 3 mounted in and connected to the front and rear headers 4 and 5 respectively, which headers are in turn connected with

the steam drum or cylinder 6 disposed above the tubes. The fire box 7 is located as usual beneath the tubes above the grates 8, the ash pit 9 being disposed beneath the grates, and access to the fire box and the ash pit being obtained through the doors 11 and 12 respectively. The products of combustion are delivered from the boiler after their passage around the tubes through the outlet flue 13 connected to the chimney or stack in the usual manner.

The structure thus far described may be of well known or preferred construction, but the baffles utilized in connection with the boiler constitute the essence of this invention. These baffles, preferably two in number, are designated by reference character 14 and 15, and as will be apparent from the drawings, they are located in spaced relation between the ends of the boiler tubes; the rear baffle 15 extending from the steam drum 6 in a substantially vertical plane downwardly to a point somewhat above the lowermost tubes 3, while the front baffle 14 is preferably inclined forwardly from its lower to its upper end for the purpose of retarding and directing forwardly the products of combustion from the fire box, thus insuring the heating of the forward ends of the boiler tube before these products pass downwardly at the rear of the front baffle.

Each baffle is of hollow construction and is provided with a series of transversely disposed thimbles 16 forming a water tight connection with the walls of the baffle, of suitable size to accommodate the water tubes 3 which extend therethrough and fit loosely within the thimbles. This construction permits the ready removal and replacement of the tubes when necessary for repairs or other purposes without interference by the baffles.

It will be observed that the rear baffle in this form of invention does not extend downwardly to the bottom of the boiler tubes but terminates some distance upwardly from the lowermost tubes. The position of this baffle and the inclined position of the front baffle causes the products of combustion from the fire box 7 to travel upwardly around the forward ends of the tubes 3 and then downwardly and rearwardly between the baffles and then upwardly back of the rear baffle before being discharged through the flue 13. This tortuous passage of the hot products

of combustion results in a thorough heating of the water tubes and produces a very efficient boiler. The baffles, which are of course, subjected to the hot gases and other products of combustion become highly heated, and in order to preserve their life and also to utilize the heat absorbed by the baffles, I have provided them with fluid connections which maintain a continuous circulation of fluid through the baffles, as will now be described.

The upper end of the rear baffle 15 is connected with the top of the drum 6 so as to conduct steam therefrom which is superheated in the baffles as will now be explained. The steam entering the upper end of the rear baffle 16, flows downwardly to the lower end and thence through one or more connecting pipes 18 to the lower end of the front baffle 14. It then travels upwardly in the front baffle to the upper end thereof, from which it is conducted by a delivery pipe 19 to the point where this superheated steam is to be used. It will be apparent that the steam in the baffles is coolest where it enters the upper end of the rear baffle and is hottest where it leaves the upper end of the front baffle. The direction of flow of the steam through the baffles being counter to the direction of passage of the products of combustion around the baffles, results in the most efficient heat exchange with the result that the maximum number of heat units are absorbed from the products of combustion during their passage around the boiler tubes and around the baffles. The steam thus superheated in its passage through the baffles prevents them from becoming overheated and warped or distorted, and insures longevity of the construction.

In plants where superheated steam is not desired my invention may be utilized to heat the feed water to the boiler either by causing the incoming water to pass through the baffles en route to the boiler or by maintaining a circulation of water through the baffles and a tubular, feed water heater wherein the heat units absorbed in the baffles are given off in the heater.

By reference to Fig. 2, it will be observed that in this embodiment of my invention, the supply pipe 21 leading to the upper end of the rear baffle 22 is connected with the outlet end of a tubular feed water heater 23 of well known construction and the delivery pipe 24 from the front baffle 25 discharges at 26 into the intake end of the feed water heater. In the heater the water flows downwardly around the tubes 30, extending between the headers which are disposed near each end of the heater in the usual manner. The baffles 22 and 25 are connected at their lower ends by one or more pipes 27 so that a closed circuit through the baffles and the feed water heater is established and in this

circuit, the water continuously circulates, traveling downwardly through the rear baffle, thence through the pipe 27 to the front baffle, then upwardly and through the pipe 24 is eventually delivered to the feed water heater. The incoming fresh water is delivered from any suitable source through a pipe 28 to the feed water heater, where it flows through the tubes 30 to the opposite end of the heater and back to the pipe 29 surrounded during such travel by the hot water delivered by the pipe 24 so that the heat taken up by the water in the baffles is delivered to the incoming fresh water in the feed water heater, this heated fresh water being delivered through pipe 29 to the drum of the boiler. In this construction, therefore, the same water is continuously circulated and re-circulated through the feed water heater and baffles, and if this water is originally comparatively pure, the amount of deposit and sludge left in the baffles is negligible.

In this instance also, the baffles as will be observed from Fig. 2 are slightly different in form and arrangement from those described in connection with those described in Fig. 1. The rear baffle extends entirely to the bottom of the tubes 3 and the front baffle, instead of being inclined forwardly, is disposed in a vertical plane parallel with the rear baffle. Both baffles in this instance are provided with thimbles for the reception of the boiler tubes similar to those previously described and removal and replacement of the tubes may be effected without interference by the baffles.

It will be apparent from the foregoing that I have provided a baffle structure in a water tube boiler which not only deflects and directs the passage of the products of combustion so as to produce the most efficient heating, but furthermore, the heat delivered to the baffles themselves may be utilized either in superheating steam or in heating water which is used to promote the efficiency of the boiler. In addition to this, the baffles themselves are protected and prevented from becoming burnt out or dangerously overheated so that their life is greatly prolonged.

It is believed that my invention, the preferred constructions in which it is embodied, and many of the advantages of this invention will be understood from the foregoing without further description, and while I have shown and described those embodiments which at present appear preferable, it should be manifest that the invention is capable of wide variation in its details of construction without departing from the spirit of the invention as defined in the following claims.

I claim:

1. In a water tube boiler, the combination

- of a steam drum, a plurality of water tubes, a fire box beneath the forward ends of said tubes, a forward hollow baffle extending upwardly adjacent to said fire box, a 5 rear hollow baffle extending downwardly from said drum in spaced relation to said forward baffle, thimbles disposed in said baffles through which said water tubes extend, means connecting the lower ends of said baffles together, a pipe for supplying fluid to the upper end of said rear baffle so that said fluid travels downwardly in said rear baffle, thence through said connecting means to the lower 10 end of said forward baffle and thence upwardly in said forward baffle, and a pipe for delivering said fluid from said upper end of said forward baffle.
2. In a water tube boiler, the combination of a steam drum, a plurality of water tubes, a fire box beneath the forward ends of said tubes, a forward hollow baffle extending upwardly toward said drum, a rear hollow baffle extending downwardly from said 25 drum, each of said baffles being provided with thimbles through which said
- tubes extend, a connection between the lower ends of said baffles, a pipe connecting the upper end of the rear baffle with the top of said drum through 30 which steam from said drum enters said baffle, and a pipe connected with the upper end of the forward baffle for delivering the steam, which has been superheated in said baffles, therefrom.
3. In a water tube boiler, the combination of a steam drum, a plurality of vertically disposed baffles arranged in spaced relation and positioned to provide circulating spaces above and beneath alternate baffles, each 35 baffle being provided with water tube thimbles, a pipe connecting the lower ends of said baffles, a fire box disposed forwardly of the front baffle, a connection between the top of said drum and one of the rear baffles 40 through which steam from the drum is delivered to the baffles, and a pipe for delivering from the upper end of the front baffle the steam which has been superheated in said baffles.

J. M. SULLIVAN.
